VEGETABLE SHREDDER

Herbert A. Clemens, Fort Wayne, Ind.

Application March 2, 1955, Serial No. 34,828

Term of patent 14 years

(Cl. D89—1)

The characteristic features of my design for the shredder disclosed reside in the base portions having the configurations as shown and in the relation of the hopper portion to the base portions.

I claim:

The ornamental design for a vegetable shredder, as shown and described.
